[57] CLAIM

The ornamental design for a spectacle frame, as shown
and described.

DESCRIPTION

FIG. 1 is a front, top and right side perspective view of
a spectacle frame showing my new design;

FIG. 2 is a front elevational view thereof;

FIG. 3 is a right side elevational view thereof, the left
side elevational view being a mirror image of FIG. 3;

FIG. 4 is a top plan view thereof;

FIG. 5 is an enlarged sectional end view thereof taken
along the line 5—5 in FIG. 2 and looking in the direc-
tion of the arrows;

FIG. 6 is an enlarged sectional end view thereof taken
along the line 6—6 in FIG. 2 and looking in the direc-
tion of the arrows; and

FIG. 7 is an enlarged sectional end view thereof taken
along the line 7—7 in FIG. 4 and looking in the direc-
tion of the arrows.

FIG. 8 is a front, top and right side perspective view of
a second embodiment of a frames of spectacles showing
my new design;

FIG. 9 is a front elevational view thereof;

FIG. 10 is a right side elevational view thereof, the left
side elevational view being a mirror image of FIG. 10;

FIG. 11 is a top plan view thereof;

FIG. 12 is an enlarged sectional end view thereof taken
along the line 12—12 in FIG. 9 and looking in the direc-
tion of the arrows;

FIG. 13 is an enlarged sectional end view thereof taken
along the line 13—13 in FIG. 9 and looking in the direc-
tion of the arrows;

FIG. 14 is an enlarged sectional end view thereof taken
along the line 14—14 in FIG. 11 and looking in the
direction of the arrows.
